UNITED STATES PATENT OFFICE.

LOUIS S. LOCKWOOD, OF NORTH TONAWANDA, NEW YORK, ASSIGNOR TO THE RU-
DOLPH WURLITZER MANUFACTURING COMPANY, OF NORTH TONAWANDA, NEW
YORK, A CORPORATION OF NEW YORK.

TRACKER MECHANISM FOR MUSICAL INSTRUMENTS.

Application filed April 30, 1927. Serial No. 187,821.

The object of this invention is the provision of a reliable compensating tracker mechanism which will automatically maintain proper registration of the music sheet perforations with the tracker ducts under all conditions, whether the sheet tends bodily to deviate from its central tracking position or expands or contracts more or less under atmospheric changes, the improved tracking mechanism being especially desirable for comparatively wide music rolls such as required for orchestral and moving picture organs.

In the accompanying drawings:—

15 Figure 1 is a front elevation of the tracker mechanism. Figure 2 is an enlarged rear elevation, partly in section, of the sectional tracker and its compensating devices. Figure 3 is a top plan view of the tracker mechanism. Figure 4 is an enlarged cross section on line 4—4, Fig. 1. Figure 5 is an enlarged sectional elevation of the pneumatics, the electric switches, the planes of the sectional portions being on line 5—5, Fig. 3. Figure 20 25 6 is a sectional perspective view of the last-mentioned parts. Figure 7 is a diagram of the thermostatic units and their pneumatically-controlled switches.

Similar characters of reference indicate 30 corresponding parts throughout the several views.

The tracker box or frame 10 may be of ordinary construction. The tracker is expansible and contractible and composed of 35 a suitable number of sections, preferably three, the end sections 11 and 13 of which are movable relatively to the central section 12. These several sections are also movable collectively in a lateral direction so 40 that the tracker may be shifted bodily to correct faulty registration of the music sheet 14 shown by dotted lines in Fig. 1. For this purpose, the tracker-sections are mounted on a laterally-sliding carriage 45 which in the construction shown, comprises parallel horizontal bars 15 tied together at their ends by cross bars 16. The latter slides on guides 17 in the form of horizontal rods parallel with the bars 15 and fixed 50 at their ends in the cheeks of the tracker box. The tracker-sections have longitudinal guide-grooves 18 which receive the carriage-bars 15.

Pneumatic mechanism is preferably employed for shifting the tracker-carriage, 55 that illustrated by way of example including a pair of oppositely-acting pneumatics 19, 20 from either of which motion is transmitted to the carriage by a lever 21 and links 22, 23. The lower link 22 also serves 60 as a rigid coupling-bar between the movable boards of the pneumatics 19, 20. A spring 24 whose free upper end interlocks with a notch 25 of the link 22 tends to return the latter and the movable boards of said pneumatics to their normal position. These pneumatics are applied to opposite sides of a duct-board 26 having a main suction passage 27 (Figs. 5 and 6) whose upper end is connected by a tube 28 with the main exhaust chamber of a musical instrument, not shown, while the lower end of said passage leads by a cross-passage 29 to the interior of both pneumatics 19, 20, said cross passage containing bleeds 30. In the upper part of the block 26 are vertical flushing passages 31 having horizontal extensions 32 from which branches 33 lead into the pneumatics 19 and 20, respectively. Leading to the flushing passages 31 are tubes 34, 35 preferably having their inlets arranged adjacent to the paths of travel of opposite edges of the music sheet. To these inlets are applied valves or pallets 36, carried by the rear arms of controlling levers 37, the front arms 38 of which constitute laterally-swinging fingers adapted to bear against or lie adjacent to the edges of the music sheet. These finger levers are fulcrumed on brackets 39 secured to the back of the end tracker-sections. 90 Light springs 40 tend to close the flushing valves 36.

The mechanism so far described operates to shift the tracker carriage and the sectional tracker bodily relatively to the music roll, (not shown) to automatically center the musical sheet to correct faulty registration of its perforations with the tracker-ducts.

The mechanism for automatically adjusting or lengthening or shortening the tracker to compensate for transverse expansion or contraction of the music sheet due to climatic or atmospheric influences is preferably constructed as follows:—

Arranged above and below the tracker are

thermostatic rods or members 41 each fixed at one end in one of the tracker-box cheeks by a set screw 42 or other suitable means, while its opposite end is free and operatively connected with one of the movable tracker-sections 11 or 13 by a laterally-swinging lever 43, so that as the rods shorten or lengthen, they shift the end tracker-sections simultaneously toward or from the 10 fixed section, the two rods being mounted to expand in opposite directions for this purpose, as shown in Fig. 2. Each of the levers 43 is pivoted to the adjacent tracker box cheeks and its forked inner end is pivotally connected to the corresponding tracker-section by a pin 44, the companion thermostatic rod 41 being pivoted to the lever near its fulcrum to multiply the movement of the tracker-section. An electric 20 heating coil 45 is applied to each of the thermostatic rods and these coils are included in a suitable heating circuit, Fig. 7, containing automatically-controlled switches generally designated 46, two being employed in 25 the particular embodiment of the invention herein shown and described. The fixed members 47 of these switches may be carried by blocks 48 secured to opposite sides of the duct-board 26, while their movable members 30 49 are secured to the movable boards of auxiliary or switch pneumatics 50, 51 applied to opposite sides of said duct-board, the heating circuit being closed when both of said auxiliary pneumatics are inflated, as shown 35 in Fig. 1, and being broken when either of those pneumatics is collapsed. The latter, which may be smaller than the power pneumatics 19, 20, communicate by branch-passages 52 with the passages 32. As the 40 smaller auxiliary pneumatics communicate with the interior of the motor pneumatics by the passage 52, 32, and 33, those small pneumatics are exhausted through the motor pneumatics and are flushed through the 45 tubes 34, 35, when the flushing valves 36 are opened by the action of the music sheet on the valve fingers 38.

The operation of the tracking mechanism is as follows:—

Upon starting the instrument to which the mechanism is applied, the main controlling pneumatics 19, 20 are exhausted by their communication with the exhaust chamber hereinbefore referred to, but they are kept 50 distended by the link 22 so long as the music sheet remains in its normal, properly-tracking position. However, the switch pneumatics 50, 51 being connected with the suction-source through said main pneumatics, 55 are collapsed under these conditions, as shown by dotted lines in Fig. 1, thus opening the switches 47, 49 and breaking the heating circuit. At the same time the flushing valves are closed, their fingers 38 remaining 60 undisturbed. Should the sheet swerve 65

ily from its proper tracking position, say toward the left, it will trip the left-hand finger 38 and open the corresponding valve 36, thereby flushing the left hand main pneumatic, destroying the equalized partial vacuum in the two main pneumatics and allowing the right-hand one to collapse, causing the tracker carriage with the tracker to be shifted as a unit in the opposite direction, by the links 22 and 23 and the lever 21 and 70 75 restoring the proper registration between the sheet-perforations and the tracker ducts, in a well-known manner.

When the music sheet swells or expands under atmospheric influences, its edges trip 80 the fingers and open the valves 36, flushing and expanding both switch pneumatics and closing the heating circuit. The coils thereupon heat the thermostatic rods 41, expanding 85 them and shifting the movable tracker sections away from the fixed tracker section accordingly or proportionately to compensate for the expansion of the sheet and maintain it and the tracker in proper register. When the sheet contracts, the fingers are released and the flush valves are allowed to 90 close under the action of their springs, thus again collapsing the switch pneumatics, opening the switches and breaking the heating circuit. The thermostatic rods are now 95 allowed to cool and contract, thereby shifting the movable tracker-sections toward the fixed section to follow up the shrinking of the sheet. In this manner, the sectional tracker is lengthened or shortened automatically, the heating-circuit being either broken or established by the variations or fluctuations 100 in the width of the sheet, thus maintaining the proper relation between the sheet and the tracker under all conditions. 105

Originally, the sections of the tracker and associated parts are so assembled and adjusted that the tracker is somewhat shorter than the width of a normal music sheet or roll, in order to cooperate properly with a shrunken roll. Therefore, upon putting a 110 roll of normal width in the tracker box, the thermostatic elements come into play temporarily, and as they are automatically controlled by the fingers, said elements receive 115 the required amount of heat from time to time to expand the tracker to fit a normal roll.

Various modifications of the invention may be made within the scope of the claims, and I do not therefore wish to be limited to the particular embodiment herein shown and described.

I claim as my invention:—

1. Tracker mechanism for automatic musical instruments, comprising an expandible tracker, and thermostatic means under control of the music sheet for automatically adjusting the length of the tracker to variations in the width of the sheet. 125 130

2. Tracker mechanism for automatic musical instruments, comprising an expansible tracker, and electro-thermostatic means under the control of the music sheet for automatically adjusting the length of the tracker to compensate for variations in the width of the sheet.
3. Tracker mechanism for automatic musical instruments, comprising a sectional tracker, and thermostatic means under control of a music sheet, for automatically moving the tracker-sections to lengthen or shorten the tracker in accordance with the expansion or contraction of the music sheet.
4. Tracker mechanism for automatic musical instruments, comprising an expansible tracker, and means for automatically adjusting the length of the tracker including a thermostatic member operatively connected with the tracker, an electric circuit, a heater for said thermostatic member arranged in said circuit, and controlling means for said circuit under control of the music sheet.
5. Tracker mechanism for automatic musical instruments, comprising an expansible tracker, and means for automatically adjusting the length of the tracker, including a thermostatic member operatively connected with the tracker and having a heating coil, an electric circuit containing said coil, and a switch in said circuit controlled by the music sheet.
6. Tracker mechanism for automatic musical instruments, comprising an expansible tracker, means for automatically adjusting the length of the tracker including a thermostatic member having an electric heating coil, a circuit containing said coil, a switch in said circuit, and a controlling pneumatic
- for said switch under control of the music sheet.
7. Tracker mechanism for automatic musical instruments, comprising an expansible tracker, means for automatically adjusting the length of the tracker including a thermostatic member having an electric heating coil, a circuit containing said coil, a switch in said circuit, a controlling pneumatic for said switch, a conduit communicating with said pneumatic and having a flushing valve, and means under control of the music sheet for controlling said flushing valve.
8. Tracker mechanism for automatic musical instruments, comprising a tracker having relatively-movable sections, and means under control of the music sheet for automatically adjusting the tracker-sections, said means including thermostatic rods operatively connected with different sections, respectively and mounted to expand lengthwise in opposite directions.
9. Tracker mechanism for automatic musical instruments, comprising a tracker having a fixed section and adjustable sections movable toward and from the fixed section, thermostatic rods mounted to expand lengthwise in opposite directions and each operatively connected with one of said adjustable sections, and heating means for said rod under control of the music sheet.
10. In tracker mechanism for automatic musical instruments, an expansible tracker having relatively movable sections, a shifting lever connected to one of the sections, and a thermostatic rod fixed at one end and having its free end pivotally connected to said lever.

LOUIS S. LOCKWOOD.
